UNITED STATES PATENT OFFICE.

EDUARDO MALAVARCA, OF NEWARK, NEW JERSEY.

DESIGN FOR A DOLL.

58,392.

Specification for Design.

Patented July 12, 1921.

Application filed March 29, 1920. Serial No. 369,752. Term of patent 7 years.

To all whom it may concern:

Be it known that I, EDUARDO MALAVARCA, a subject of the King of Italy, residing at Newark, in the county of Essex and State of New Jersey, have invented a new, original, and ornamental Design for a Doll, of which the following is a specification, reference being had to the accompanying drawing, forming part thereof.

The drawing shows a front view of the doll.

I claim:

The ornamental design for a doll, as shown.

EDUARDO MALAVARCA.
